(57) **CLAIM**

The ornamental design for a sign holder, as shown and
described.

DESCRIPTION

FIG. 1 is a top, front perspective view of a sign holder,
showing our new design;

FIG. 2 is a front view thereof, the rear view being a mirror
image thereof;

FIG. 3 is a right side view thereof;

FIG. 4 is a left side view thereof;

FIG. 5 is a top view thereof; and

FIG. 6 is a bottom view thereof; and,

FIG. 7 is a top, front perspective view of the sign holder in
an environment of use.

In the drawings, the broken lines depict unclaimed subject
matter only and form no part of the claimed design. The long
dash-short dash bolded broken lines indicate the bounds of
the claimed design and otherwise form no part of the
claimed design.
